UNITED STATES PATENT OFFICE.

WARREN S. BELDING, OF ENGLEWOOD, ASSIGNOR TO THE BELDING MOTOR AND MANUFACTURING COMPANY, OF CHICAGO, ILLINOIS.

COIL-GUARD FOR ARMATURES.

SPECIFICATION forming part of Letters Patent No. 415,696, dated November 26, 1889.

Application filed July 7, 1888. Serial No. 279,314. (No model.)

To all whom it may concern:

Be it known that I, WARREN S. BELDING, a citizen of the United States, residing at Englewood, in the county of Cook and State of Illinois, have invented certain new and useful Improvements in Coil-Guards for Armatures; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to improvements in armatures to facilitate the forming of the wire coils upon the core of the armature and to prevent the displacement of the coils after they have been formed. I accomplish my object by combining with the core any desired number of coil-guards, as will be herein-after described, and specified in the appended claims.

In the accompanying drawings, Figure 1 is a blank from which is to be formed one of the coil-guards. Fig. 2 is a view of one of the coil-guards formed from such a blank as is shown in Fig. 1. Fig. 3 is an end view of a portion of an armature-core having upon it three coil-guards, one of which contains a coil. Fig. 4 is a side view of the section of core shown in Fig. 3. Fig. 5 is a transverse section through a portion of a core and coil. Fig. 6 is an end view of a Gramme ring provided with my coil-guards. Fig. 7 is a section taken through said ring. Fig. 8 is a view of a modified form of the guards.

It has been found in the manufacture of armatures that it is difficult to form the coil around the end of the bobbin-space. The wires, instead of lying one upon the other in regular order, as is required to form a perfect coil, slip and spread so that it has been nearly impossible to make coils which were correct in form and which would remain so in use. To avoid this difficulty, armature-cores of the Pacinotti type have been cast with lateral as well as radial polar extensions. Thus a channel would be formed around the

end of the bobbin-space, which channel could 50 be wound full of wire; but these lateral polar extensions add to the weight of the armature, which is in some cases objectionable. Furthermore, many armature-cores are now made by combining a number of annular metal 55 plates arranged side by side in planes at right angles to the axis of the armature. In the use of such plates each may be cut with radial polar extensions, so that when the plates are combined the complete cylinder will have 60 radial polar extensions. Then, when the wire is wound, it does not build up correctly in turning at the end of the bobbin-space. My coil-guards are to be applied at such ends to retain the wire and cause it to build up there, 65 as it does between the radial polar extensions.

When the Gramme ring is used, it is difficult to build up the wire into coils extending over the same space and containing equal 70 quantities of wire. However much care may be exercised in spacing, it is frequently found that the last bobbin-space to be wound is too large or too small, in consequence of which the value of the armature is reduced. To 75 this ring my guards are applied to divide it into mathematically-equal bobbin-spaces.

Referring to the drawings, Fig. 1 shows a blank having the parallel slits A' A' cut toward the center from each end. These slits 80 divide the blank into two tongues A² A² and the lobes A³ A³. The latter are preferably rounded to conform to the exterior of the end of the coil. Bending said tongues away from and said lobes toward the eye, we have formed 85 the complete guard A, as shown in Fig. 2, the lobes A³ A³ standing lengthwise in vertical, and the tongues A² A² lengthwise in horizontal, planes. The slits A' A' are separated 90 from each other a distance equal to the width of the finished coil B, Fig. 3, so that when the lobes A³ A³ are turned up there will be a space between them equal to the desired width of the coil. This uncut portion forms a web A⁴, whose width between the tongues A² A² is 95 equal to the radial thickness of the core C, so that when said tongues are turned up the space between them will be equal to the radial

thickness of the core. Said core is shown in the drawings as being composed of a series of sheet-metal plates C^2 , applied to each other in planes at right angles to the axis of the armature. The core may, however, be formed otherwise.

In applying the guard to the core it is presented to the end of the core at the bobbin-space, and one tongue is pushed over the inner and the other over the outer face of the core between the radial extensions C' until the portion A^4 rests against the core C . Another guard applied similarly to the opposite end of the same bobbin-space prepares that portion of the core to receive the coil. The wire is now wound around the complete bobbin-space between the lobes A^3 , one strand being placed closely beside the other until a single layer of wire quite fills the space between said lobes and the radial extensions C' . Another layer is now formed upon the first, the strands of wire in the second layer being held upon those of the first at the ends of the core by the lobes A^3 of the guard A . More layers are added until the space between the radial extensions C' is even full, and each layer is kept in place at the ends of the core by the lobes A^3 .

It will be understood that in order to secure the highest efficiency the space between the radial extensions should be quite filled by the coil, in order that the average distance of the aggregate of the wires from the iron of the outer portion of the polar extension shall be reduced to the minimum; but it is also understood that none of the strands of the coil are to be permitted to rise above said extensions, for if they do they catch on the field-magnets when the armature rotates. I have found that these strands remain in place between the radial extensions so long as they are drawn taut, and that when any of them are allowed to become slack they tend to move out of place. I have also found that if the strands on the outer portion of the coil are arranged in regular layers around the ends of the bobbin-space, and any of such strands are then allowed to move laterally from the layers beneath them, the strands so moving laterally are slackened to such an extent as to allow them to rise between the radial extensions C' ; or should any of the inner strands move laterally then the outer strands will, by such moving of the inner strands, lose their support and tension and be free to undergo this displacement.

When my guard is used, the entire coil may be wound in full and even layers and the strands held against lateral movement by the lobes $A^3 A^3$; hence there is no loss of tension in any of the strands, and the entire coil assumes and retains a correct form.

When the Gramme ring is used, the guards are applied one against the other around the entire ring, as shown in Fig. 6. The guards are cut of the same size and of such size as

that the desired number will just fill the ring. Thus the ring is spaced evenly into equal bobbin-spaces, and when each guard is wound full the coils are all properly spaced and contain equal quantities of wire.

The guards may be insulated from the core C by interposing insulation material E between said core and the guards.

When applied to the Pacinotti ring, the lower tongue A^2 may be omitted, so that the guard will consist only of the lobes $A^3 A^3$, web A^4 , and the single upper tongue A^2 . (See Fig. 8.) The latter should in this case be wide enough to fit closely between the radial extensions C' , whereby it is engaged and held in place.

I claim as my invention—

1. In an armature, the combination, with the core, of coil-guards applied to the ends of the core, said guards having lobes A^3 and a web A^4 , connecting said lobes, and a tongue or tongues for securing the guard to said core, substantially as described.

2. In an armature, the combination, with the core, of coil-guards applied to the ends of the core, said guards having lobes $A^3 A^3$ and a web A^4 , connecting said lobes, and two tongues, one extending over the exterior of said core and the other over the interior of said core to secure said guard to said core, substantially as shown and described.

3. In an armature, the combination, with the core, of coil-guards applied to the ends of the core, said guards having a web A^4 and lobes A^3 , extending outward from opposite sides of said web, and tongues $A^2 A^2$, extending inward from the edges of the web intermediate to the lobes $A^3 A^3$, substantially as shown and described.

4. The combination, with an armature having the radial extensions C' , of coil-guards applied to the ends of the core of said armature opposite the spaces between said radial extensions, said guards having lobes $A^3 A^3$, separated from each other a distance equal to the space between the radial extensions, and tongues A^2 , extending into the spaces between said extensions, and a web A^4 , connecting said lobes and tongues, substantially as described.

5. In an armature having a core composed of a series of sheet-metal plates C^2 , applied to each other in planes at right angles to the axis of the armature, the combination, with such core, of coil-guards applied to the ends of the core, said guards having lobes $A^3 A^3$ and a web A^4 , connecting said lobes, and a tongue or tongues extending from said web over said core, substantially as described.

6. In an armature, the combination, with the core composed of the metal plates C^2 , of coil-guards applied to the ends of the core, said guards having the lobes $A^3 A^3$, tongues $A^2 A^2$, and a web A^4 , connecting said lobes and tongues, substantially as described.

7. In an armature, the combination, with

the core composed of the metal plates C², of
coil-guards applied to the ends of the core, said
guards having lobes A³ A³, tongues A² A², and
a web A⁴, connecting said lobes and tongues,
5 and an insulation material E, interposed be-
tween the core and said guards, substantially
as described.

In testimony whereof I affix my signature in
presence of two witnesses.
